ANIMATED SIGN

Bruce Roberts, Hollywood, Calif., assignor to
Frank McQuoid, Los Angeles, Calif.

Application June 25, 1937, Serial No. 150,238

8 Claims. (Cl. 40—52)

This invention relates to an improvement in animated signs and, more particularly, to animated signs operated and illuminated by electricity.

5 The sign includes a plurality of movable characters actuated into and out of display position in repetitious order. Such signs have been proposed heretofore, as for example, signs having panels suspended on endless chains and signs 10 having characters coming in and out of view driven by rack and gear mechanisms. This invention, however, provides a much more simple and economical means of animation and one in which the movement of the sign is more fascinating.

It is accordingly an object of my invention to provide a display of physical characters in sequence, such as, one letter following another in the spelling of words; this, without the necessity 20 of mechanisms connected to the motor of the sign.

Another object of my invention is to provide means of assuring that the characters stay in their intended position during the operation of 25 the sign so that it may not readily get out of order.

A further object of my invention is to provide means wherein the characters of this sign may be readily changed or adjusted.

30 My invention possesses other advantages, and has other objects which may be more readily apparent from a consideration of one of the embodiments of my invention. For this purpose I have shown a form in the drawings accompanying and forming part of the present specification. I shall proceed to describe this form in detail, which illustrates the general principles of my invention; but it is to be understood that this detailed description is not to be taken in a limited sense, since the scope of my invention is best 35 defined by the appended claims.

Referring to the drawings:

Figure 1 is a front view of a sign embodying my invention;

45 Fig. 2 is a rear view thereof;

Fig. 3 is a detailed section taken along the plane 3—3 of Fig. 2;

Fig. 4 is a rear view of the sign in an operative position;

50 Fig. 5 is a top plan view taken along the plane 5—5 of Fig. 4;

Fig. 6 is a detailed section taken along the plane 5—5 of Fig. 4;

55 Fig. 7 is a vertical section taken along the plane 6—6 of Fig. 5;

Fig. 8 is a top plan view of the switch mechanism, together with a combined wiring diagram;

Fig. 9 is a view of a section embodying another form of displaying the characters; and

Fig. 10 is a vertical section taken at right angle to the plane of Fig. 9.

The front elevation of the sign is shown in Fig.

1. It may conveniently comprise a case 11, having a window 12, and a translucent fixed sign 10 14. The window 12 may be of clear glass for the protection of the movable characters 20, 21, 22, 23, 24, 25, 26, 27 and 28. The screen 13, (Figs. 1, 2, 3, 4, and 7) is to hide from view other parts 15 of the mechanism.

One of the main features of the device is a detached rolling element, preferably a ball, as shown by 15, (Figs. 2, 3, 4, 5, 7, and 9 and 10). This ball rolls along a slotted track 16, (Figs. 2, 3, 4, 5, 7, 9, and 10), which is supported at an inclined plane on the back of the vertical frame member 17, in (Figs. 2, 3, 4, 5, 6, 7, and 9).

The character holders 30, 31, 32, 33, 34, 35, 36, 37, 38, 39 and 50 are pivotally journaled in their respective bushings 40, 41, 42, 43, 44, 45, 46, 47, 48, 49 and 51, which are mounted at right angles through the vertical frame 17, as shown in (Figs. 2, 3, 4, and 5). Also, in this form shown in (Figs. 2, 3, 4, 5, 6 and 7) the character holders 30, 31, 32, 33, 34, 35, 36, 37, 38, 39 and 50 30 are extended at right angles to their respective bushings and are disposed in the path of the ball 15 and have free clearance through the slot in the inclined track 16.

Fastened at the lower extremity of the inclined track 16 and onto the back of the vertical frame 17, is a driving motor capable of propelling the ball up the inclined track to its full length.

Preferably, this motor shall be of the electromagnetic type. There is one with a moving armature disposed to strike a ball as it rolls into a position susceptible to being propelled when a switch is turned on. Such a device is practical but will not be as economical or quiet in its operation as the motor recommended and described herein.

In Figs. 2, 3, 4, 5, and 7 is seen a solenoidal coil 18, in line with the inclined track 16, and fastened at its lower extremity so that a steel ball will roll freely through the inside of this coil 50 when propelled by the force of gravity. Disposed in the path of the ball is a movable steel finger 53, (Figs. 2, 3, 4, 7 and 8) hinged at its lower end to the base of the sign. Properly spaced and interposed in the path of the moveable finger 53 55

are the extensions, 54 and 55, of a shuttle member 56, (Fig. 8) frictionally mounted in a ways 57. The shuttle member 56 has a diagonal extension 58, which slides and presses against a 10 diagonal extension 59, of dielectric material fastened to the contact arm 60. The contact arm 60 is tensionally opposed away from the contact arm 61. The arrangement in the switch is such that the steel ball passing through the coil 10 pushes before it the steel finger 53. This in turn actuates the shuttle arm 56, by striking the extension 54 so that the contact points supported, by the arm 60 and 61 are brought together.

If an electric circuit of sufficient power is 15 connected by these contact points, immediately the magnetic force set up within the coil causes the steel ball 15, and the steel finger 53, to rush toward the center of the coil, 18. The current is caused to remain on for a period because the 20 shuttle member 56, is held in engaged position by frictional contact with its way 57. However, at a time when the steel ball has reached the center of the coil, the steel finger 53, also has arrived at a point to strike the extension 54, of the shuttle member 56, which when moved, disengages the contact points supported by the contact arms 60 and 61, causing the current to be turned off. During the period the ball has travelled from the 25 outside to the center of the coil it gains enough 30 momentum to continue to the upper end of the track, assuming the character holders are in a raised position.

It may be seen that with the use of alternating current of commercial frequency that the relationship of the speed of the ball and its distance of travel will be such as to cause slightly varying forces to be applied to it. To overcome an occasional extra hard shock at the upper end of the track, a shock absorber of a pendulum type 52, (Figs. 2 and 4), is used.

The extended portion of the character holders disposed in the path of the ball are formed with a tongue and recess arrangement in alternate sequence, as shown in (Figs. 5 and 6). These 45 extensions are all of the same length except the one nearest the motor, 51, and are all mounted in their bushings in line and are equally spaced. The length of each extension is more than the distance between each point of suspension and not 50 more than the distance between two such suspension points.

A description of such parts whose function may be independently related has been given. And I shall describe their relationship in operation, together with other parts whose function is more apparent during the operation of the sign. Consider the sign in a position in which the letters are all out of display position (Fig. 2). By placing the ball 15, at the upper end of the inclined 60 track 16, the force of gravity causes it to roll along the track toward its lower end. Disposed in its path is the extension 65 of the trigger element 66 hinged in journals 67 and 68. The flat spring 62 is sufficiently flexible to allow the arm 65 to give way and the trigger shaft 66 to turn and recede without stopping the ball. The ball continues down the track running against the extension of the character holder 30 which together with the character 20 are of light weight. The 65 ball being comparatively heavy and the pitch of the track of sufficient grade will cause the character holder 30 to pivot in its journal 40 and bring the character 20 into display position.

Since the extension of the holder 30 is swung 75 in an arc, its tongue 69 passes through the recess

70 of the holder extension 31, seen in (Fig. 6). And while the ball is still pressing the holder 30 upward, it moves the holder 31 in the same manner in which the holder 30 is moved, bringing into display the character 21.

While the holder 30 is still being held up by the presence of the ball and the holder 31 is swung into its respective arc, the recessed portion of the holder 31 moves out of range of the tongue of the holder 30. The ball going further down 10 the track causes the portion of the shank of the holder 31, which is not recessed, to come up under the tongue of the holder 30, and hold it up after the ball has passed contact with the holder 30. It may be seen that the same relationship 15 between the holders 31 and 32 will occur as occurred between the holders 30 and 31. And as each holder extension is successively moved from the path of the ball it will pivotally turn and bring its respective character successively into 20 display, and that each holder will hold in position the holder which preceded it.

As the ball proceeds from the upper end of the track to the lower end it is necessary to have character holders at every equal space, although 25 there may be no characters actually attached thereto, because the sequence must be unbroken to hold up the preceding characters. Also, the owner of the sign, at his discretion, may wish to change the characters, or their spacing.

As the ball continues to roll down the track it urges before it the character holders in succession, which are held in a lateral position by their interlocking action and more particularly, by the 30 last character holder.

As it is a further object of the sign that the characters shall stay in display position for a period and then simultaneously recede from view, a trigger element, 66, with extended arms, 65 and 19, is provided (Figs. 2 and 4), and pivotally fastened at the side of the track 16 in journals 67 and 68.

The arm 19 (Figs. 2, 4 and 7) is provided with a spring 62 and a catch 64, angularly and properly attached thereto and disposed a short distance in the path of the character holder 50. When the ball urges the holder 50 in its arc and passes beneath its extended tip, the shank of the holder 50 is caught and sustained above the catch 64. This causes all the character holders and their characters to remain in a co-extended position after the ball has passed contact and has 50 rolled into the coil.

The action of the motor, which has been described, takes place and causes the ball to roll back up the track since no obstructions will be in its path until it again passes the arm 65 of the element 66. In so doing, the trigger element is pivoted carrying the arm 19 and its catch 64 away from the plane of operation of the character holder 50. This holder being released is drawn by the force of gravity into its original position, as are each of the characters in immediate reverse succession, producing an apparent simultaneous recession of characters.

Thus, it may be seen that the sign is in the same position as it was prior to its cycle of operation and that the ball is subject to gravity as before, and, in summary: will roll down the track causing the characters to come into display in succession; 70 while the trigger element holds the last and consequently, all the characters and holders in position: the ball rolls into the motor and is propelled back up the track during which time the characters will be collectively held in display and the 75

holders free and clear for the upward passage of the ball. After tripping the trigger at its upper extension, the characters simultaneously recede and the ball is stopped at the end of the track 5 and again repeats the cycle.

Any suitable means may be employed to attach the characters to the character holders, such as a tongue and slot arrangement. In case the characters themselves are longer than the spaces 10 between them they may be journaled away from the plane of their axis so that they recede in orderly arrangement without interference, as seen in Fig. 3. It is not intended to confine the nature 15 of the characters to letters as it may be seen that they might easily be comprised of many other types of characters, such as figure cut-outs or numerals.

In Figs. 9 and 10, I illustrate another embodiment of my invention, in which the axis upon 20 which the character holders turn are in the plane of the vertical frame. Referring to these figures, is illustrated a plurality of character holders, 21A, 22A and 23A, journaled in this manner. Each rear extension of each character holder 25 is disposed in the path of the ball, below its center axis and is so shaped as to have a tab, similar to 23A (Fig. 9), which is covered and held in position by the succeeding character holder as it comes into position after the ball has passed over 30 it. The track 16A has a larger recess than the slot in the track 16 of the previous illustration. A trigger arrangement, holding and releasing the last character holder, is used in a like manner as in the embodiment of my invention previously 35 illustrated.

A suitable means of illuminating the sign is used illustrated by electric lamps, 63, 63, (Figs. 5 and 7).

It is understood that the embodiment of the 40 invention described herein is only one of the many embodiments this invention may take, and I do not wish to be limited in the practise of the invention, nor in the claims, to the particular embodiment set forth.

45 What I claim is:

1. In an animated sign, a fixed frame, a plurality of movable characters, individually journaled to the frame so as to come into and out of display position, means of consecutively bringing 50 the characters into display position, means of collectively retaining the characters in display position, and a means of simultaneously removing the characters from display position.

2. In an animated sign, a plurality of moveable characters, individually pivoted to come into and out of display position and disposed in the path of a detached rolling element, a detached rolling element, a motor to propel the detached 55 rolling element, means of successively bringing the characters into display position, means of collectively retaining the characters in display posi-

tion, and means of collectively removing the characters from display position.

3. In an animated sign, the combination of a plurality of changeable characters, a plurality of character holders individually pivoted to a fixed 5 frame, and disposed in the path of a detached rolling ball, a detached ball, electro-magnetic means of propelling the detached ball, means of consecutively urging the characters into display position, means of interlocking the character 10 holders to retain the characters in display position, means of unlocking the character holders and collectively removing the characters from display position.

4. In an animated sign, a plurality of changeable characters, a plurality of pivotally supported character holders, a ball, an inclined track for the ball, a motor to propel the ball, means for consecutively bringing the characters into display 15 position, means for simultaneously removing the 20 characters from display position.

5. In an animated sign, an inclined track, a rolling element to roll thereon, pivotally mounted and interlockable character holders disposed in the path of and moveable by the rolling element, 25 changeable characters attached to the character holders, a trigger element to sustain and release all the character holders actuated by the rolling element, and an electro-magnetic motor to propel the rolling element up the inclined track, 30

6. In an animated sign, an electric motive mechanism comprising a ferrous rolling element, a solenoidal coil capable of being freely transversed by the rolling element, contacts actuated by a shuttle mechanism to control the coil, a 35 moveable finger controlling the shuttle mechanism, allowing the rolling element to move to an extreme position within the coil before being energized and to effect the contacts so that the energy endures until the rolling element reaches 40 the center of the coil.

7. In an animated sign, electro-magnetic means to propel a ball, an inclined track for the ball to roll on, pivotally journaled character holders disposed in the path of the ball, changeable characters attached to the character holders, relief display means surrounding all the characters, means of urging the characters in and out of 45 display.

8. In an animated sign, a fixed frame, a plurality of character holders pivotally journaled thereto, a plurality of changeable characters attached to the characters, extensions of the character holders disposed in the path of a ferrous ball, an inclined track, a ferrous ball to roll on 50 the track, a solenoidal coil arranged to directly 55 propel the ferrous ball, a switch mechanism to control the solenoidal coil, a trigger element to retain and release the characters and holders in and out of display position. 60

BRUCE ROBERTS.
